INVENTOR

Robt. Heneag

UNITED STATES PATENT OFFICE.

ROBERT HENEAGE, OF BUFFALO, NEW YORK, ASSIGNOR TO HIMSELF AND EDWD. O. BALL, OF SAME PLACE.

IMPROVEMENT IN HEMP-BRAKES.

Specification forming part of Letters Patent No. 22,399, dated December 21, 1858.

To all whom it may concern:

Be it known that I, ROBERT HENEAGE, of the city of Buffalo, in the county of Erie and State of New York, have invented certain new and useful Improvements in Machines for Dressing Flax and Hemp; and I do hereby declare that the following is a full and exact description thereof, reference being had to the accompanying drawings and the letters of reference marked thereon.

The nature of my invention relates to the arrangement and combination of parts, as herein described, for the purpose of producing an improved and practically-working machine for dressing flax and hemp.

Figure I is a side elevation of my said improved machine. Fig. II is a plan of the same. Fig. III is a longitudinal section. Fig. IV is an end elevation showing the reversing mechanism.

Letters of like name and kind refer to like parts in each of the figures.

A represents a table upon which the flax or hemp is laid in order to be carried to the brake.

B B² is the brake. This consists of two fluted rollers, the one placed above the other, and both revolving together. Journals are formed upon their ends, which have bearings in the standards D. There is a slot in each standard, which allows of a vertical movement to the upper roller, B, in order to compensate for the different thicknesses of flax or hemp which may happen to be placed upon the table. The weighted lever H, bearing upon the journal of the upper roller, makes an elastic or yielding pressure upon said roller. The cog-wheel E is placed on the end of the lower roller, B², and meshes in with pinion F. These two fluted rollers constitute what I call the "brake," and they also operate as feeders to feed the flax or hemp to the beater, and also to return the hemp after it has been subjected to the action of the brake and beater to the table.

C² is a strip of metal, which is let in longitudinally across the face of the revolving cylinder C. These metal strips project half or three-fourths of an inch above the face of the cylinder, and, arranged as they are with the cylinder C, constitute what I call the "beater."

K is a shell of metal, which lies parallel with the roller B² and close to it, and forms nearly a quarter-circle around it. As the flax or hemp passes through the brake it passes over this shell, and it has the effect to hold the flax or hemp to the beater, so that the shives are effectually beaten out and separated from the fiber as the flax or hemp passes over the shell. As the parcel of flax passes through the brake the latter end will quickly pass the shell and fall down upon the roller J³, where the beater strikes it and completes the work.

I is an outside case or cap, which sets on the frame over the beater.

J represents a revolving apron, which serves the purpose of returning the flax to the hands of the workman after it has been subjected to the action of the beater.

L represents a stationary bottom, making the segment of a circle with the cap I. Except at its termination, it has a slight and short curve upward for the purpose of throwing off and outwardly the current of air generated by the revolution of the beater.

M represents a blower, which may or may not be used with the machine. I do not consider it an indispensable part of the machine.

N O P represent bands and pulleys arranged in any well-known manner for the purpose of applying power to the machine.

R S T U V, reversing mechanism, consisting of lever, clutch-shaft, and loose pulleys, arranged in a common and well-known manner, for the purpose of reversing the motion of the revolving brake, (or feed-rollers B B²), so that a parcel of hemp may be run in through the brake and into the chamber as far as practicable, and then run out again upon the table and have its ends reversed, and then subjected to the same action over again.

W is the main frame of the machine.

X shows a chamber or recess for the purpose of passing the hemp into during the process of dressing, as herein described.

Operation: (See Fig. III.) When flax is to be dressed, it is in the first place spread upon the table A in a proper quantity to be fed to the brake. The revolving brake or fluted rollers B B² draw it in and crush or break the woody part thereof (or shive) and carry it along over the shell K, where the beater acts upon it and beats out the shives. The flax follows

the direction indicated by arrow 2, and passes onto the apron J and under the roller J², and along to the hands of the workman. When hemp is to be dressed, the apron J is not used. It is thrown out of gear and remains stationary. A parcel of hemp is then put upon the table A and carried to the brake. The brake crushes or breaks it, and it passes over the shell K, where the beater strikes it and beats it against the shell K and separates the shives therefrom. It moves along past the apron in the direction indicated by arrow 3 and into the chamber or recess X. It is not allowed to pass entirely through the brake; but while a portion of it is still upon the table and within the grasp of the workman the motion of the brake is reversed, and it is run back upon the table, and the workman immediately changes its position upon the table and runs its undressed part through the brake, as before, so that the brake and beater have acted upon its entire body and fully dressed it. The motion of the brake is then again reversed, and the parcel of hemp is run back upon the table to the hands of the workman, and the work of

the machine upon the parcel is complete. This process is repeated for each parcel put upon the table. Hemp is thus very nicely dressed, and the shives separated therefrom without wasting or snarling the fiber and while it remains straight and smooth.

I claim—

1. The combination of the reversing mechanism with the brake B B², beater C C², and shell K, substantially as herein described, and for the purpose of dressing hemp, as set forth.

2. The combination and arrangement of the brake B B² with the revolving beater C C², shell K, and revolving apron J, for the purpose of dressing flax, substantially as herein set forth.

3. The arrangement of the chamber X within the machine for the purpose of affording room for the movements of the hemp while being dressed, substantially as herein described.

ROBT. HENEAGE.
